DESIGN FOR A DRESSING TABLE

Mary H. McKenzie, Duluth, Minn.

Application September 20, 1945, Serial No. 122,211

Term of patent 7 years

(Cl. D33—14)

To all whom it may concern:

Be it known that I, Mary H. McKenzie, a citizen of the United States, residing at Duluth, in the county of Saint Louis and State of Minnesota, have invented a new, original, and ornamental Design for a Dressing Table, of which the following is a specification, reference being had therein to the accompanying drawing, forming part thereof, in which cover in an open position, of a dressing table, showing my new design.

Figure 2 is a view in front elevation, with the lid or cover in a closed position.

I claim:

The ornamental design for a dressing table, as shown.

MARY H. MCKENZIE.
